United States Patent Office

Des. 204,130

Patented Mar. 22, 1966

204,130

COMBINED POST AND RAILING

Louis Blum, Pittsburgh, Pa., assignor to Blumcraft
of Pittsburgh, Pittsburgh, Pa.

Filed July 12, 1962, Ser. No. 70,893

Term of patent 14 years

(Cl. D13—7)

FIGS. 1, 2, 3, and 4 respectively are perspective, front, side, and plan views of a combined post and railing embodying my new design.

I claim:

The ornamental design for a combined post and railing, as shown and described.
